ATTORNEY

UNITED STATES PATENT OFFICE.

CECIL A. ROUSH, OF UPPER SANDUSKY, OHIO.

SHADE-ROLLER HOLDER.

1,272,114.

Specification of Letters Patent. Patented July 9, 1918.

Application filed November 1, 1917. Serial No. 199,692.

To all whom it may concern:

Be it known that I, CECIL A. ROUSH, citizen of the United States, residing at Upper Sandusky, in the county of Wyandot and 5 State of Ohio, have invented certain new and useful Improvements in Shade-Roller Holders, of which the following is a specification.

My invention relates to new and useful 10 improvements in shade roller holders, and is more particularly of the type which is detachably secured to the window frame.

An important object of my invention is to provide a device of the above mentioned 15 character, including means whereby the shade holder's supporting arm may be adjusted longitudinally as well as vertically.

Another object of my invention is to provide pads upon the arms of the shade holder 20 which engage the frame of the window, thereby preventing the bracket or holder from scratching or marring the frame.

A further object of my invention is to provide a device of the above mentioned 25 character including a pair of spring arms which secure the holder in close engagement with the frame of the window, when the holder is attached thereto.

A still further object of my invention is 30 to provide a device of the above mentioned character, which is strong, durable, inexpensive to manufacture, efficient in practice.

Other objects and advantages will be apparent during the course of the following 35 description.

In the accompanying drawing forming a part of the description and wherein like numerals are employed to designate like parts throughout the same,

40 Figure 1 is a front elevation of the invention.

Fig. 2 is a vertical sectional view of the same, taken on the line 2—2 of Fig. 1.

Fig. 3 is an enlarged transverse sectional 45 view of a portion of the holder taken on the line 3—3 of Fig. 1, and

Fig. 4 is a rear elevation of a portion of the device broken away.

In the drawings herein for the purpose of 50 illustration is shown a preferred embodiment of my invention, the numeral 1 designates the end portion of the usual type of shade roller.

My shade roller holder is constructed from 55 any light, strong material and consists of an elongated vertical arm 2, having an elong-

gated vertical opening therein. The lower end of this member is curved inwardly to form a spring or resilient portion 4, and is provided on its inner side with a pad 5. 60 The upper end 6 of the member 2 is twisted at right angles to the body portion and is provided with a central aperture, for the reception of the shank and of the shade roller. 65

Secured to the back of this vertical member 2 by means of rivets or the like, is a second substantially vertical strip 7 and is bent to form the portion 8, which is spaced a substantial distance from the member 2 70 directly back of the elongated opening 3. The inner side of this portion 8, or the side thereof adjacent the member 2 is provided with the vertical corrugations 9 for a purpose which will be hereinafter set forth. 75 The upper end of the strip 7 is bent inwardly similar to the portion 4, to form the spring arm 10. This spring arm is also provided on its inner face with a pad 11.

Arranged between the two vertical members 8 and 2, is a horizontal strip 12, having its ends bent inwardly and at right angles thereto to provide the extensions 13, which is more clearly shown in Fig. 3. One of these extensions is provided on its inner 80 surface with a pad 14, and the other extension is adapted to have a threaded opening for engagement with a thumb screw 15, having a pad secured on its abutting end. As more clearly shown in Fig. 4 this strip 12 85 is provided on its inner face with vertical corrugations 16, the longitudinal edges of which are cut away as at 17 for a purpose to be hereinafter set forth. Upon the outer side of strip 12 intermediate the ends 90 thereof, is arranged a plate 18 provided at each corner thereof with a hook 19 adapted to be bent over the longitudinal edges of the strip 12 and to engage the cut away portions 17. The plate 18 is mounted upon the strip 12 so that the strip may slide longitudinally through the hoops of the plate. This plate 95 is further provided with a central opening therethrough, the purpose of which will be hereinafter set forth. 100

Adapted to move vertically in the elongated opening 3 in member 2, is a slide 20, and with engagements 21 adapted to engage the inner and outer faces of the member 2. This slide is provided with a central threaded opening to receive a thumb screw 22, the inner end of the shank there- 105 110

of being adapted to pass through the central opening in the plate 18 to engage the strip 12. It will be noted that by screwing the thumb nut 22 inwardly, the inner end 5 of the shank will engage the strip and force the corrugations thereon into engagement with the corrugations 9 on the member 8.

To apply this shade holder to the frame 10 of a window, the angular extensions of the strip 12 are placed so as to snugly embrace the sides of the frame by adjusting the thumb screw 15. It will be noted that this portion of the bracket remains stationary 15 upon the frame and that the remainder of the holder may be moved vertically to adjust the holder to the height desired or horizontally to receive shade holders of 20 various widths. By unscrewing the thumb screw 22 the pressure against the strip 12 is diminished which in turn lessens the friction between the corrugations 16 thereon, and the corrugations 9 formed upon the member 8, thereby allowing the movable 25 part of the holder to slide up or down with relation to the strip 12. By loosening the thumb nut 22 further, the movable part of the holder may be moved horizontally along the strip 12, so as to adjust the holder to 30 various lengths of shade rollers. When any vertical adjustment is made, the slide 20 will operate in the opening 3. When the holder is in position upon a window frame, it will be seen that the spring arms 4 and 35 10 will be in close engagement with the frame, thereby securely holding the same to the frame.

It is to be understood that the form of 40 my invention herewith shown and described 45 is to be taken as a preferred example of the same and that various changes in the shape, size, and arrangement of parts may be resorted to without departing from the spirit of the invention or the scope of the subjoined claims.

Having described my invention, I claim:

1. A shade roller holder comprising a 50 stationary horizontal member, said member being provided with vertical corrugations thereon, adjustable vertical members having vertical corrugations thereon and means carried by the vertical member for clamping the corrugations upon each member into engagement.

55 2. A shade holder comprising a stationary horizontal strip, said strip carrying vertical corrugations, an adjustable vertical member carrying an elongated opening, a plate mounted upon the horizontal strip, vertical corrugations carried by the movable member, and means slidably mounted in the opening of the movable member and engaging the horizontal strip

for forcing the corrugations thereon into engagement with the corrugations formed 65 upon the movable member.

3. A shade holder comprising a stationary horizontal member having corrugations thereon, a plate horizontally movable thereon, and having an opening therein, a vertical movable member, a slide thereon having a threaded opening, and a thumb screw operable in said slide for engagement with the horizontal member through the opening in said plate. 75

4. A shade holder comprising a stationary horizontal member, means for securing said member to a window frame, means for supporting the shade roller, a vertical movable member, and spring arms carried there- 80 by for engagement with the window frame.

5. A shade holder comprising a vertical member having its lower end bent to form a spring arm and having its upper end twisted to right angles to the body portion of said vertical member and provided with a perforation, a second vertical member secured to the first named member and having its upper free end bent to form a spring arm to coact with the spring arm 90 formed upon the first vertical member, a horizontal arm interposed between the two vertical members, and means for adjustably clamping the two vertical members to the horizontal arm. 95

6. A shade holder comprising a stationary horizontal member having vertical corrugations upon its inner face, the longitudinal edges of said inner face being cut away, a vertical movable member having corrugations thereon to coact with the corrugations on the horizontal member, a plate slidably mounted upon the outer face of said horizontal member, said plate having a plurality of fingers bent over the longitudinal edges of said horizontal member to engage the cut away portion thereof, and means carried by the vertical member for adjustably clamping the same upon the horizontal member. 100

7. A shade holder comprising a vertical movable member consisting of a pair of spaced parallel vertical arms one of which is provided with vertical corrugations, a stationary horizontal arm interposed between said vertical arms and provided with vertical corrugations to coact with those upon the vertical arm, and means carried by the vertical arm for adjustably clamping the vertical member to the horizontal arm. 115 120

In testimony whereof I affix my signature in presence of two witnesses.

CECIL A. ROUSH.
